PUNCHING MACHINE

Ulrich Kölle, Berlin, Germany, assignor to International Business Machines Corporation, New York, N. Y., a corporation of New York

Application September 15, 1933, Serial No. 689,509
In Germany April 21, 1933

10 Claims. (Cl. 164—113)

This invention relates to punching machines and more particularly to machines of the type in which punching is effected in record cards, column by column, under control of manually operable keys.

In punching machines of the type to which the improvements of the present invention apply, a group of twelve keys is usually provided to individually select any one or more of a group of twelve punches to perforate the index point positions of a column of a record card. In such machines the punching operation follows immediately upon depression of a key and is completed before the key returns to normal position. As a result, in case the operator depressed the wrong key, the corresponding wrong punch would be automatically operated and incorrectly punch a record. Consequently, the record would be spoiled and would have to be discarded and a new record perforated all over again. The disadvantages of such a procedure are obvious, and where accuracy of punching is essential, time consuming verifying operations are resorted to after the records are punched.

The principal object of the present invention is to overcome the disadvantages of previous systems by devising a means for checking the accuracy of the key selection before the record is actually punched.

Specifically, there is provided a signal lamp for each key position which is illuminated upon depression of the corresponding key. Concurrently with the depression of any key and the illumination of its related lamp, a punching circuit is partially completed to the related punch. This circuit is, however, not fully completed until a following key depression is effected to select another punch at which time the first selected lamp is extinguished and the second selected one lighted and another partial circuit established to be fully completed upon the third key operation.

By thus delaying the punch operation one step or one key operation, the operator is given an opportunity to note whether the correct key has been depressed and to correct the error without recording the same in the card. If an error is detected it is merely necessary to prevent completion of the partial circuit by cancelling or restoring it to its normal condition, without interfering with the previous operations.

Various other objects and advantages of the invention will be obvious from the following particular description of one form of mechanism embodying the invention or from an inspection of the accompanying drawings; and the invention

also constitutes certain new and novel features of construction and combination of parts herein-after set forth and claimed.

In the drawings:

Fig. 1 is a sectional detail of the essential operating mechanism of the punching machine.

Fig. 2 is a detail of the punch carriage escape-
ment mechanism.

Fig. 3 is a detail showing the arrangement of the keyboard and checking lamps.

Fig. 4 is a wiring diagram of the electric circuits of the device.

Figs. 5 and 6 are details of a reversing relay.

The punching machine is generally of the form shown in the Lee and Phillips Patent No. 1,772,186, granted August 5, 1930 and the description thereof will be limited to the features essential to an understanding of the present invention and the manner in which the invention may be applied to such a punching machine.

In Fig. 1, punch selecting magnets 10 are provided, there being one for each of the twelve index point positions of the record card R. Energization of magnet 10 will attract its armature to rock an arm 11 in a counterclockwise direction about its pivot 12, thus moving key 13 downwardly to rock a bell crank 14 which has connection with an interposer 15 which is suitably mounted for horizontal reciprocation. The forward end of each interposer 15 is suitably guided between an operating bar 16 and the upper end of a punch 17.

Forward movement of an interposer 15 will position its widest portion between bar 16 and a punch 17 so that subsequent counterclockwise rocking of bar 16 about pivot 18 will move the interposer and punch downwardly to perforate the record card R. A notch 20 in the interposer cooperates with a bail 21 to rock the same in a counterclockwise direction when the interposer is moved toward the left. Rocking of bail 21 toward the left will raise a hook-shaped link 22 to close a pair of contacts 23.

As will be explained in connection with the circuit diagram, contacts 23 complete a circuit through the punch magnet 24, causing it to attract its armature 25 and through linkage generally designated 26, draw downwardly on the bar 16 to cause depression of the selected punch. Depression of key 13 may, of course, be effected independently of magnet 10 for the purpose of manually controlling punching operations. A pair of contacts 19 is adapted to be opened by one of the links 26 near the end of its downward movement at which time also, a finger 39 engages the free end of link 22 and moves it to the right, out of engagement with con-

tacts 28 whereby the latter are permitted to re-open.

Disposed beneath the interposers 15 is a ball 27 which is carried by rod 28 upon one end of 5 which is secured an arm 29 (see Fig. 2) for operating the escapement mechanism. The escapement mechanism comprises a holding pawl 30 pivoted at 31 to the frame of the machine and a stepping pawl 32 loosely pivoted on rod 28 and 10 normally urged by a spring 33 into engagement with the teeth 34 on the upper edge of rack 35. Rocking of rod 28 in a counterclockwise direction under action of bar 16 rocking on an interposer 15 will lower pawl 30 into engagement with a 15 tooth 34 to hold rack 35 in position while punching is being effected. This action at the same time raises pawl 32 out of engagement with teeth 34 and by virtue of its loose connection with rod 28 will move slightly toward the right in readiness to intercept the next tooth 34 when the rod 28 is returned to its original position.

The rack 35 is suitably mounted for horizontal movement in the frame of the machine and may be moved toward the right to the position shown 25 in Fig. 1 wherein a record R is placed in position with the first column thereof in line with the punches 17. Gear teeth cut on the underside of the rack cooperate with a suitable gear 36 which is connected to the usual spring barrel 37 30 which tends to move the rack toward the left and which effects such movement under control of the escapement mechanism just described. Rack 35 is provided with the usual pusher 38 which advances the record R, column by column, 35 as the rack is advanced step by step.

Thus far, the device is similar to the usual punching machine and may be operated as such by depression of keys 13. For the purposes of the invention an auxiliary set of keys 40 (Fig. 3) 40 is provided, one for each of the twelve index point positions of the card. For each key 40 there is also provided a lamp 41 arranged in a similar order and marked as shown, if desired. Associated with each key 40 are two pairs of contacts 42, 43 45 (Fig. 4) which are adapted to be closed upon depression of the related key and to open when the key is released. In the diagram (Fig. 4) only four keys 40 and their circuit connections are shown, but it will be understood that the remaining keys 50 are similarly arranged.

A correction key 44, marked C is provided which is depressed when an error is detected and a "last column key" 45 marked L is provided for depression after the last key 40 is operated. Key 44 55 upon depression closes contacts 46 and 47 (Fig. 4) and opens contacts 48 and 49. Key 45 closes contacts 50 and 51.

The operation of the device may best be understood in connection with the operation of the 60 machine to punch a specific number. Assume that the number 876 is to be punched and that the record is in position as in Fig. 1 with the first column beneath the punches 17.

Current is supplied from a suitable source to 65 negative side of line 52 and positive side 53. Depression of "8" key 40 will close contacts 42, 43 in the "8" position and a circuit will immediately be traceable as follows: negative line 52, contacts 48 of correction key 44, wire 55, normally 70 closed contacts 57c of relay magnet 57, wire 58, relay magnet 59, wire 60, "8" key contacts 42, "8" relay magnet 54, wire 61, relay magnet 62, wire 63 to positive line 53. Relay magnet 54 will 75 close its contacts 54a, 54b and 54c of which contacts 54a will establish a holding circuit as fol-

lows: from line 53, wire 63, relay magnet 62, wire 64, "8" relay magnet 54, contacts 54a, wire 64, normally closed relay contacts 56d, wire 55, contacts 48 to line 52. At the same time, closure of contacts 54c complete a circuit to "8" lamp 41 as follows: from line 53, "8" wire 65, "8" lamp 41, "8" contacts 54c, wire 66, wire 55, contacts 48 to line 52. The "8" lamp 41 will thus be illuminated to indicate that the "8" key 40 had been depressed.

The corresponding punch selecting magnet 10 will, however, not be energized at this time since there is no circuit completed therethrough. In addition to the two completed circuits just traced a third circuit is also completed upon closure of 15 contacts 59a (due to energization of relay magnet 59) as follows: from line 52, wire 67, contacts 59a, wire 68, relay magnet 57, wire 69 to line 53, causing closure of contacts 57a and 57b and opening of contacts 57c.

Relay 57 is of the so-called reversing or double step type; that is, one energization of the magnet 57 will shift the contacts and a second energization will return them. The essential elements of such a relay are shown in Figs. 5 and 6 25 and will be briefly described. Upon energization of magnet 57 its armature 70 and an integral arm 71 will be rocked in a counterclockwise direction. At the free end of arm 71 is pivoted a spring pressed pawl 72 which is in engagement 30 with a ten-toothed ratchet 73. A spring pressed member 74 serves as a detent. Rocking of armature 70 and arm 71 will elevate pawl 72 to advance ratchet 73 one tooth and rotate the rod 75, upon which it is mounted, a like distance. 35 Shaft 75 carries a cam 76 (Fig. 6) of pentagonal outline which cooperates with contacts 57a, 57b and 57c through a pin 77 in such manner that contacts 57a and 57b close and contacts 57c open when the high points of cam 76 lie directly beneath pin 77. Since ratchet 73 has ten teeth and cam 76 has five low points and five high points, it is obvious that a single operation of magnet 57 will open contacts 57c and close contacts 57a and 57b and a second energization will 40 permit them to resume the positions they occupy 45 in Fig. 6.

The initial energization of magnet 57 through the above traced circuit will cause opening of contacts 57c and thereby cause deenergization of relay magnet 59. At this point then, the "8" lamp 41 will be illuminated and the contacts of reversing relay 57 will be in their shifted positions, but no punching will have been effected.

In accordance with the number selected for 55 punching, the "7" key 40 is now depressed and a circuit will immediately be completed as follows: from line 52, contacts 48, wire 55, contacts 57b (now closed), wire 78, magnet 79, wire 80, "7" contacts 43, "7" relay magnet 81, wire 82, 60 relay magnet 83, wire 63 to line 53. Magnet 83 will close its points 83a and the partially completed circuit to the "8" punch selecting magnet will now be completed as follows: from line 53, "8" wire 84, "8" punch selecting magnet 10, 65 contacts 54b (now closed), wire 85, contacts 83a (now closed), contacts 56b, contacts 19, contacts 48 to line 52. This circuit is shown in heavy full lines for convenience in tracing. Contracts 48, 19 and 56b are normally closed, contacts 54b were 70 closed upon the depression of the "8" key and contacts 83a closed as an incident to depression of the second or "7" key.

Energization of the "8" punch selecting magnet 10 will advance the "8" interposer into position 75

above the corresponding punch and at the same time cause closure of contacts 23 which complete the circuit to punch magnet 24 to punch an "8" in the record card and advance the same to the next column. Closure of contacts 23 also completes a circuit from line 53, contacts 23, wire 86, contacts 49, wire 87, magnet 56 to line 52. Magnet 56 is similar in arrangement to double step magnet 57 and reverses its related contacts at each energization so that at this time its contacts 56a, 56c and 56e are closed and 56b and 56d open.

Opening of contacts 56d, breaks the holding circuit of the "8" relay magnet 54 and permits "8" lamp 41 to extinguish. Relay magnet 62 in the holding circuit will also be deenergized at this time.

A new holding circuit for the "7" relay magnet 81 is now set up as follows: from line 53, wire 63, relay magnet 83, wire 82, "7" magnet 81, contacts 81a, wire 88, contacts 56c (now closed), wire 55, contacts 48 to line 52. Closure of contacts 81c will cause illumination of the "7" lamp 41 and closure of contacts 81b will prepare a partial circuit to the "7" punch selecting magnet 10. Energization of relay magnet 79 as explained above will close its contacts 79a to complete a circuit from line 52, wire 67, contacts 79a, wire 68, magnet 57, wire 69 to line 53, thus returning the contacts 57a, 57b, 57c to the positions shown in the diagram.

The third key to be depressed is the "6" key 40 and it will cause energization of the "6" relay magnet 54 and illumination of the "6" lamp 41 in the same manner as explained in connection with the "8" key. The incidental energization of relay magnet 62 will close its points 62a to complete the partial circuit to the "7" punch selecting magnet 10. This circuit is emphasized in heavy dotted lines and is traceable as follows: from line 53, "7" wire 84, "7" magnet 10, contacts 81b, wire 90, contacts 62a, contacts 56a (now closed), contacts 19 and 48 to line 52.

Magnets 56 and 57 are again energized; the first, upon closure of interposer contacts 23 and the second upon closure of relay contacts 59a so that after the third key operation the contacts of relay 56 are in normal position and those of relay 57 are in shifted position.

The next key depression will set a magnet 54, the next a magnet 81 and so on with the holding circuits alternated between these relays magnets and the completion of the punching circuits being effected alternately through operation of magnets 83 and 62. It will, of course, be obvious that repeated depression of the same key will first set one of the magnets 54, 81 and then the other in the corresponding position.

If a key 40 has erroneously been depressed and a holding circuit set up through one of the magnets 54 or 81 and the corresponding lamp 41 lighted, the operator may depress the correction key 44 to open contacts 48 which, it will be recalled, lie in the holding circuits of both magnets 54 and 81. These circuits are thus interrupted and the lamp 41 extinguished. Key 44 also serves to restore the double step relays 56 and 57 to their initial position as in the drawings, if one or the other is in its alternate position when key 44 is depressed. If relay 56 has been shifted, closure of contacts 46 will complete a circuit from line 52, magnet 56, wire 87, contacts 46, closed contacts 56e, wire 69 to line 53. If relay 57 has been shifted, closure of contacts 75 47 will complete a similar circuit from line 52,

contacts 47, closed contacts 57a, magnet 57, wire 69, to line 53. The device is now in readiness to receive a new setting.

After the last key 40 has been depressed to set the last number to be punched, it is necessary to complete the partial circuit for this number. For this purpose key 45 is provided which upon depression closes contacts 50 and 51. Contacts 51 shunt the heavy line punch selecting circuit around contacts 83a and 56b while contacts 50 10 shunt the dotted line punch selecting circuit around contacts 62a and 56a. These circuits are thus completed independently of the action of the relay magnets 62 and 83.

It will be obvious that if the operator so desires and where time permits, key 45 may be depressed after each depression of a key 40. In this manner a number to be punched may be selected and its lamp 41 illuminated, the number checked and then key 45 depressed to effect 20 punching of that number.

What is claimed is as follows:

1. In a machine of the class described, a plurality of punches for successively perforating a record, means including electrical devices for 25 successively selecting said punches for operation and means controlled by said selecting means for operating each selected punch simultaneously with the next succeeding selection.

2. In a machine of the class described, a plurality of punches, a plurality of keys corresponding thereto, means including a relay operative upon actuation of one of said keys for selecting the corresponding punch for operation and further relay means operative upon the subsequent 35 actuation of another of said keys for operating said selected punch and for simultaneously selecting the punch corresponding to the second actuated key for operation.

3. In a machine of the class described, a plurality of punches, a plurality of keys corresponding thereto, means including a relay operative upon actuation of one of said keys for selecting the corresponding punch for operation and further relay means operative upon a repeated actuation of said key for operating said selected punch and for simultaneously causing a reselection thereof for further punching operation.

4. In a machine of the class described, a plurality of punches, a plurality of corresponding 50 keys, an operating circuit for each punch, and means controlled by each key for partially establishing the circuit for its corresponding punch and for completing another circuit corresponding to another punch.

5. The invention set forth in claim 4 in which means is provided for restoring said partially established circuit to normal condition.

6. In a machine of the class described, a plurality of punch selecting keys, a signal circuit 60 and a punch selecting circuit for each key, means operative upon actuation of a key for completing its signal circuit and partially establishing its punch selecting circuit and means independent of said actuated key for subsequently completing said partially established circuit and for interrupting said signal circuit.

7. In a machine of the class described, a plurality of punches, a selecting magnet for each punch, a circuit for each selecting magnet including a pair of contacts, a second pair of contacts in series with all of said circuits, a plurality of keys corresponding to said punches, means controlled by one of said keys for closing the pair of contacts in the circuit of the correspond-

ing selecting magnet and further means controlled by another of said keys for closing said second pair of contacts to complete the selecting circuit of the first operated key.

5 8. The invention set forth in claim 7 in which indicating means is provided and controlled by the keys to indicate the circuit whose contacts are closed.

9. In a card perforating machine, a punch, an
10 operating key therefor, a pair of relays each adapted to cause an operation of said punch and

means controlled by the successive operation of said key for causing said relays to alternately control the operation of said punch.

10. In a card perforating machine, punches, a corresponding number of keys, a pair of relays 5 for each key for controlling the operation of the related punch, said relays being arranged in groups each comprising a relay of each pair and means for rendering said groups of relays alternately responsive to the operation of said keys. 10

ULRICH KCLM.
